United States Patent Office.

WILLARD P. BROOKS, OF BLOOMINGTON, ILLINOIS.

Letters Patent No. 93,593, dated August 10, 1869.

IMPROVEMENT IN THREE-HORSE EQUALIZERS.

The Schedule referred to in these Letters Patent and making part of the same.

To all whom it may concern:

Be it known that I, WILLARD P. BROOKS, now of Bloomington, in the county of McLean, and State of Illinois, have invented a new and valuable Improvement in Method for Working Three Horses Abreast; and I do hereby declare that the following is a full, clear, and exact description of the construction and operation of the same, reference being had to the annexed drawings, making a part of this specification, and to the letters and figures of reference marked thereon.

Figure 1 of the drawings is a top plan view of my invention.

Figure 2 is an edge view of the same.

My invention relates to means for equalizing the draught between a team of three horses, or other animals, working abreast; and

It consists in a novel combination and arrangement of devices, which effectually accomplish the above-named object.

The letter A, of the drawings, represents a bar or plate, having a grooved circular head, as shown, and being formed at its opposite or small end with a series of pin-holes.

The letter B represents a hook, adjustable in the pin-holes above mentioned, and the letter C is a chain, attached to the rear side of plate A, as shown, and working and resting in the groove of the circular head of plate A.

The letter D represents a clevis, pivoted to plate A, as shown, and having an arm which passes over the circular head of frame A, outside the chain above mentioned.

This arm serves to keep the chain in its groove, and to aid in turning around the load attached to the main part of the clevis.

What I claim as my invention, and desire to secure by Letters Patent, is—

A draught-equalizer, having plate A, hook B, chain C, and clevis D, constructed and arranged substantially as specified.

In testimony that I claim the above, I have hereunto subscribed my name, in the presence of two witnesses.

WILLARD P. BROOKS.
